US00D649894S

(12) **United States Design Patent**
Daniels et al.(10) **Patent No.:** **US D649,894 S**
(45) **Date of Patent:** **** Dec. 6, 2011**

(54) ELECTRONIC TOKEN AND DATA CARRIER	3,754,214 A	8/1973	Matsumoto et al.
(75) Inventors: Dean Daniels , Rosemount, MN (US); William Stifle , Rogers, MN (US)	3,757,305 A	9/1973	Hedin
(73) Assignee: ATEK Products, LLC , Brainerd, MN (US)	3,761,892 A	9/1973	Bosnyak
(**) Term: 14 Years	3,782,148 A	1/1974	Goldman
(21) Appl. No.: 29/330,181	3,806,882 A	4/1974	Clarke
(22) Filed: Dec. 30, 2008	3,842,629 A	10/1974	Pazer et al.
(51) LOC (9) Cl. 10-05	3,848,229 A	11/1974	Perron et al.
(52) U.S. Cl. D10/106.9	3,859,634 A	1/1975	Perron et al.

FIG. 1 is a top perspective view of an electronic token and data carrier according to an embodiment of the present disclosure;

FIG. 2 is a bottom perspective view thereof;

FIG. 3 is a top view thereof;

FIG. 4 is a bottom view thereof;

FIG. 5 is a side view thereof;

FIG. 6 is a rear end view thereof;

DESCRIPTION

Primary Examiner — Caron D Veynar
Assistant Examiner — George D Kirschbaum

(74) Attorney, Agent, or Firm — Dorsey & Whitney LLP

CLAIM

The ornamental design for an electronic token and data carrier, as shown.

FIG. 7 is a front end view thereof;
FIG. 8 is a top perspective view of an electronic token and data carrier according to a second embodiment of the present disclosure;
FIG. 9 is a bottom perspective view thereof;
FIG. 10 is a top view thereof;
FIG. 11 is a bottom view thereof;
FIG. 12 is a side view thereof;
FIG. 13 is a rear end view thereof;
FIG. 14 is a front end view thereof;
FIG. 15 is a top perspective view of an electronic token and data carrier according to a third embodiment of the present disclosure;
FIG. 16 is a bottom perspective view thereof;
FIG. 17 is a top view thereof;
FIG. 18 is a bottom view thereof;
FIG. 19 is a side view thereof;
FIG. 20 is a rear end view thereof;
FIG. 21 is a front end view thereof;
FIG. 22 is a top perspective view of an electronic token and data carrier according to a fourth embodiment of the present disclosure;
FIG. 23 is a bottom perspective view thereof;
FIG. 24 is a top view thereof;
FIG. 25 is a bottom view thereof;
FIG. 26 is a side view thereof;
FIG. 27 is a rear end view thereof;
FIG. 28 is a front end view thereof;

FIG. 29 is a top perspective view of an electronic token and data carrier according to a fifth embodiment of the present disclosure;
FIG. 30 is a bottom perspective view thereof;
FIG. 31 is a top view thereof;
FIG. 32 is a bottom view thereof;
FIG. 33 is a side view thereof;
FIG. 34 is a rear end view thereof;
FIG. 35 is a front end view thereof;
FIG. 36 is a top perspective view of an electronic token and data carrier according to a sixth embodiment of the present disclosure;
FIG. 37 is a bottom perspective view thereof;
FIG. 38 is a top view thereof;
FIG. 39 is a bottom view thereof;
FIG. 40 is a side view thereof;
FIG. 41 is a rear end view thereof;
FIG. 42 is a front end view thereof;
FIG. 43 is a top perspective view of an electronic token and data carrier according to a seventh embodiment of the present disclosure;
FIG. 44 is a bottom perspective view thereof;
FIG. 45 is a top view thereof;
FIG. 46 is a bottom view thereof;
FIG. 47 is a side view thereof;
FIG. 48 is a rear end view thereof; and,
FIG. 49 is a front end view thereof.

In the drawings, the broken line showing depicts environmental subject matter and forms no part of the claim.
